UNITED STATES PATENT OFFICE

2,440,222

BLASTING ROOM

Walter L. Keefer, Hagerstown, Md., assignor to
 Pangborn Corporation, Hagerstown, Md., a corporation of Maryland

Application March 2, 1946; Serial No. 651,641

19 Claims. (Cl. 51—8)

1

This invention relates to blasting rooms for cleaning of castings and the like, and aims generally to improve the same. The invention is particularly, but not exclusively, applicable to core knockout rooms in which a jet of water, or preferably of water and abradant, is employed to break down and blast away the molding cores used in the founding of large, hollow castings.

In such blast-rooms, it is customary to place the casting in an enclosure and project upon it a high pressure stream of water from nozzles, or blast-guns carried by operators within the rooms, or positioned adjacent a wall of the enclosure. In the latter case, the direction of projection of each jet gun relative to its mounting has been variable, and it has been customary to provide two jet guns, one to project the stream generally horizontally toward the work, and another located at a higher elevation to project a stream generally downwardly toward the work. The provision of two guns at different levels has required the inclusion of two operating stations at different levels with their respective platforms, stairways, piping, valves, etc., with accompanying disadvantages, but it has not heretofore been possible to eliminate the duplication of elements and duplication of personnel, or loss of time, of personnel in moving from one station to the other. In addition, it has been found difficult in some work to manipulate either of the blast-guns so as to obtain fully effective action in the removal of the cores from special and unusual casting shapes.

An important object of the present invention is to provide improved apparatus of this character in which the flexibility of the gun and its adaptability to the cleaning of various shapes of work is greatly increased.

Another object is to provide an improved apparatus of the character described in which the requirement for duplication of stations and equipment associated therewith is eliminated.

Another object of the invention is to provide improved apparatus of this character adapted to perform the work more expeditiously and with a minimum of lost operator-time.

Further objects and advantages of the invention, as will appear from the following detailed description of a preferred embodiment thereof, reside in the provision of improved features and arrangement of parts contributing to the realization of the aforesaid objects.

In the accompanying drawings, illustrative of a preferred embodiment of the invention:

2

Fig. 1 is a plan view partly cut away of a gun mounting section of a core knockout enclosure.

Fig. 2 is a vertical section on line 2—2 of Fig. 1.

Fig. 3 is an elevation view, taken from the plane 3—3 of Fig. 2, looking in the direction of the arrows.

Fig. 4 is an enlarged fragmentary section taken on line 4—4 of Fig. 2, in the direction indicated by the arrows.

In the illustrative embodiment shown in the drawings, the blast-room comprises an enclosure 10 having the usual entrance doors 10a (Fig. 1), the usual room pit 10b, extending below the normal floor level 10c, and suitable accessories (not shown) for transporting the castings into and from the room, and for supporting them in position to be worked upon therein.

In accordance with the present invention, a section of the wall of the enclosure 10 is replaced by a vertically slideable wall section 11, which carries a blast-gun 12; this section preferably being arranged diagonally in one corner of the room to conserve space and enable the blast-gun to discharge against a wide range of the work with a favorable angle of attack.

In the form shown, the slideable wall section 11 comprises the inner face of an operator's vestibule or cubicle, herein shown as a rectangular tower formed of side walls 13 set diagonally in the corner of room 10, closed on the room side by the sliding wall 11, open on its outer side, and overlying a part of the room pit 10b, the whole being deep enough to house the operator's platform and control equipment hereinafter described.

The blast-gun 12 (Figs. 1 and 2) may be of any conventional or special design. That chosen to illustrate the invention is of the general type to which Keefer Patent 2,369,576, of February 13, 1945, relates, but is modified to enable the structure to be carried by the vertically slideable wall 11. To this end the blast nozzle 12 is provided with a directly connected "sand-hose" 14 through which abradant is supplied, and with a universally mounted, balanced, high-pressure, fluid conduit, herein comprising a double elbow 15 having its lower vertical end flanged, and turnable in a packing ring 16, and having its upper opposed horizontal ends delivering to a coupling 17, swingable in the vertical direction.

Suitable means, as bracket 18, is employed to mount the ring on the slideable wall 11, and the lower end of double elbow 15 is supplied with high-pressure propellant, herein water, through the ring 16, which is coupled to high-pressure hose connection 19.

The universally mounted blast gun structure is also provided with control means operable from within the cubicle 11-13 by an operator on the platform 26 (hereinafter described), by which control means the nozzle 12 may be moved to discharge toward the work in any direction within the limits of the structure. In the preferred arrangement, simple and effective control means is afforded by providing the coupling 17 with a lug 20 to which is secured, as by set screws 20a, control rod 21 extending through a flexible boot 22, which is carried by and covers an aperture in the sliding wall 11.

By manipulation of control rod 21 the gun assembly may be rotated in the ring 16, and the coupling 17 and gun 12 tilted up and down in the assembly with sufficient angularity to direct the blast-jet toward the part of the work desired.

To enable observation of the direction and effect of the blast by the operator on the platform 26 (hereinafter described), a suitable window 23 is provided (Figs. 2 and 3, omitted in Fig. 1 for clarity). This window may take any desired form and be kept clean and protected from abrasive particles in any desired manner. In the form shown, the window 23 is mounted in an inclined position by a frame 24 covering an opening in the sliding wall 11, and is provided with a wash-down means in the form of a water-pipe 25 arranged adjacent its top edge and slotted or perforated to discharge a cleaning liquid against the room side of the window pane. The window 23 may also be provided with a safety screen (not shown) interposable between it and the flying particles of abrasive, core, etc., when this is desirable, and with means controllable by the operator for swinging the screen into and out of position.

As will be seen from Fig. 2, the conduits 14 and 19 are arranged to accommodate vertical movement of the slidable wall and gun assembly herein by their flexibility and depending loop arrangement. A similar arrangement may be provided to feed cleaning fluid, as water, to the wash-down sprayer 25. Suitable valve actuating means (not shown) arranged to be under control of the operator on the platform 26 (hereinafter described) are provided for lines 14 and 19, and for other lines for which this arrangement may be desirable.

Experience has shown that with normal sized large castings, best results are attained by providing for vertical movement of the gun 12 a considerable distance, exceeding eight feet in most instances, thus enabling it to assume positions in which the alternate guns of prior rooms were fixed, as well as other intermediate and in some cases more extended positions. The prior alternative gun arrangements, as above mentioned, not only lacked flexibility; they also required stairways and duplicate pipe connections, controls, etc., at the respective operators' stations because of their wide vertical separation. These necessities of the prior art are eliminated by the present invention by providing, on the exterior of the vertically slidable wall section 11, an operator's platform 26 properly located with respect to window 23 and control rod 21, and movable therewith on movement of the wall section, and by providing in a convenient location relative to the operator's platform, as in the position 27 on the sliding wall 11 adjacent the control rod 21, a push button or like control for effecting raising or lowering of the entire wall-gun-platform assembly.

Preferably also, the operator's station is provided with controls, exemplified in Figs. 2 and 3 by foot-controlled switches 28 and 28a and remote-acting motor controller 29, for controlling any desired accessories of the blasting room. Switch 28, for example, may control through suitable circuits the movement of the turntable, work conveyor, or other support on which the castings are mounted for blasting. Switch 28a, for example, may control the supply of sand, through the sand-hose 14, independently of the supply of water through the water-hose 19, so that the sand supply may be cut off when it is desired to wash the castings with a water-jet after completion of the knockout operation. Controller 29, for example, may control the pressure of the water supplied through pipe 19, as by controlling the speed of the motor driven water pump, to vary the pressure between the wide limits, say 600 to 1200 pounds per square inch, if desired. The details of such switches and remote control devices, and various modes for relating such ambulant controls to otherwise located apparatus, are well known, and thus require no further illustration here.

To obtain maximum vertical traverse of the wall-gun-platform assembly without undue extension of the height of the adjacent room walls, an especially advantageous form of movable wall section is employed in the preferred embodiment.

This form enables the maintenance of a tight closure of the blast-room at all times, and requires no casing extensions, or clear space maintenance, either above or below the normal boundaries of the blast-room. In this preferred form the sliding wall 11 is a rigidified section in the run of a flexible band 30, which may be a multiply rubber belt or curtain. This band 30 is entrained over guide rolls 31 and 32 adjacent the top 13a of the vestibule 11-13, and adjacent the bottom of the pit 10b respectively, and its ends are connected to reel-rolls 33 and 34 similarly located and outwardly spaced with reference to the blast-room from the guide rolls 31 and 32.

As will be appreciated from Figs. 1 and 2, the rolls 31 and 33 are preferably located to position the upper run of the belt 30 closely adjacent to the vestibule roof 13a. As shown in the same figures, lower rolls 32 and 34 are preferably located in the room pit, so that gun 12 may be moved to a lowermost position closely adjacent the floor level, at which position operator's platform 26 is preferably aligned with floor 10c (see Fig. 2).

The wall forming section 11 of belt 30, in the form shown, runs at its edges in guideways provided between angle-irons 35 carried by vestibule walls 13 (see Fig. 4). These angle-irons, as shown, extend from near the top of the vertical run of belt 30 to near the bottom thereof, and are spaced just sufficiently to receive the vertically movable parts of the assembly 11-30 with an easy running fit. The station-section of this assembly, as above noted, is a vertically movable plate-like section 11 for mounting the operator's platform, the blast gun, and such other parts as are desired, to travel with the station. The section 11 may take any desired form and may be a metallic plate secured to, or in the run of, the belt, and extending into or terminating just short of the guideways 35. In the simple and preferred arrangement shown in the drawings, for lightness, the section 11 is rigidified by angle-iron frame 40 suitably secured to the belt in surrounding relation to the station-section, thereby em-

bracing the window 23, boot 22, controls 21 and 27, bracket 18, etc. This frame 40 may be secured in place in any desired manner, being riveted to belt 30 in the illustrative embodiment. Operator's platform 26 is also secured to the sliding wall section 11, preferably by attaching the same to frame members 40, as shown. Frame 40 and platform 26, for lightness, are preferably constructed as skeletonized framed sections as shown, but where skeletonization is not desired, plates of metal or other suitable materials may be secured to or be employed in lieu of such framed section, and be secured to or in the vertical run of belt 30 in any desired manner.

Drying of reels 33 and 34 under control of push button 27 is effected in the form shown by gear-motor 41, suitably supported, as on shelf 42 carried by wall 13, adjacent the end of a driven roll, herein roll 33. As shown in Figs. 1 and 3, the push button control may comprise two buttons, with appropriate relays, respectively energizing motor 41 for forward or reverse motion, so that the operator at will may cause gun 12 and its associated station to move to any desired location in its vertical transverse. Limit switches, which are well known, per se, may also be provided to prevent over-travel of belt 30 and prevent damage of any parts associated therewith. These may be arranged in any desired manner. Simply, by way of example, such switches are dia-grammatically shown at 30a and 30b, Fig. 2, as adapted to be moved to motor stopping position by a part moving with the curtain 30, herein the platform 26, at the extreme limits of the desired travel thereof.

In the form shown, assuming the use of ten inch rolls for reels 33 and 34, and a vertical traverse of about eight feet for the gun 12, such traverse would represent the transfer of about three turns of belt 30 from reel 33 to reel 34, or vice versa. Since transfer of even these few turns of heavy multi-ply belting changes the effective reeling diameter of rolls 33 and 34, suitable means is provided in the driving gear for these rolls to compensate for this factor, and to simultaneously maintain the curtain wall 11, 30 taut at all times. This means in its preferred form consists of a tension chain 45-46 inter-linking driving sprockets 47 and 48 associated respectively with the reel rolls 33 and 34. Leg 45 of chain 45-46 which pulls from the respective sprockets during the reeling operation of each, has in its running part a heavy tension spring 49 so located that its traverse does not extend to either sprocket in the full run of belt 30. As will be apparent from Fig. 2, spring 49 acts to remove all slack from the tension side 46 of chain 45-46, and hence to remove all slack from belt 30 irrespective of any slackness developed in chain leg 45 by the change in effective reeling diameters of the reels 33-34. So long as leg 45 is not too tight when reels 33-34 each contain the same amount of belt, this simple arrangement will operate to satisfaction as slackness will develop in leg 45 on movement of belt 30 towards either reel from this central position. In installations where excessive slack may develop in leg 45, a swinging idler (not shown) may be positioned to press leg 45 out of vertical to thus provide a yieldable take-up; the tension produced by such idler, of course, being much less than that produced by spring 49.

With the present arrangement, the reaction of the high-pressure propellant against the nozzle of gun 12 is resisted by the turret-mounting 15-18, and transferred by it to the movable wall

11, which, in turn, is backed up by the angle irons 36 and vestibule walls 13, and the operator, carried by the platform 26, is outside the blasting room and requires no protective clothing.

5. Further, in the form shown, the weight of the turret-mounting 15-19 and jet gun 12, 14, carried on the inside of the wall 11, counterbalances more or less the weight of the platform 26 and operator carried on the outside of the wall, thus making for ease of vertical movement of the wall. Here also, the vestibule walls 13 themselves brace the structure against the reaction of the jet-gun, enabling lighter framing of the structure. If desired, however, the vestibule or pulpit may have 10 open sides and a closed rear wall, when the protection of the operator from materials being moved by travelling cranes or the like dictates such arrangement, and in such case the framing is designed accordingly.
- 15 20. Since the preferred embodiment of this invention enables the operator to adjust the position of the blast-gun and work, the character of jet employed, and the angularity of attack on the work, at will, and without moving from his seated 25 or standing position on the platform 26, it is apparent that he may obtain with this embodiment direct or oblique blasting of the most difficult shapes of work with great ease and flexibility. However, the preferred embodiment shown and 30 described is but illustrative and not restrictive of the invention herein disclosed and claimed, and inventive features and combinations of this disclosure may be embodied in other specific forms.

I claim:

35. 1. In a blast-room, an enclosure, said enclosure having a vertically slidable wall, a blast-gun projecting inwardly of and carried by said slidable wall, an operator's platform projecting exteriorly of and carried by said slidable wall, and means 40 controllable by an operator on said platform for raising and lowering said gun, platform, and wall assembly, and for controlling the discharge of said gun.
45. 2. In a blast-room, an enclosure, said enclosure having a vertically slidable wall, a bracket on the room side of said slidable wall and vertically movable therewith, a blast-gun carried by said bracket and mounted for at least limited universal movement relative thereto, an operator's platform on 50 the exterior of said slidable wall and movable therewith, a window in said slidable wall located to enable an operator on said platform to view the operation of said blast-gun, and means controllable by an operator on said platform for 55 raising and lowering said slidable wall, bracket, and platform, and for controlling the discharge of said gun.
60. 3. In a blast-room, an enclosure, said enclosure having a vertically slidable wall section, a bracket secured to the room side of said wall section, an operator's platform secured to the outer side of 65 said wall section, a blast-gun carried by said bracket, and means controllable by an operator on said platform for raising and lowering said wall section, blast-gun, and platform as a unit.
70. 4. In a blast-room, an enclosure, a flexible curtain forming one of the lateral walls of said enclosure, said flexible curtain being movable upwardly and downwardly and having a rigidified section, a blast nozzle carried by the rigidified section of said curtain on its room side, an operator's platform carried by the rigidified section of said curtain on its outer side, and means controllable by an operator on said platform for rais-

ing and lowering said curtain, nozzle, and platform assembly.

5. In a blast-room, an enclosure, said enclosure having a vertically extending opening and vertical guide-ways adjacent the lateral sides of said opening, a flexible curtain movable vertically in said guide-ways and extending across said opening, a blast-gun carried by said curtain and discharging at the room side thereof, an operator's platform carried by said curtain exteriorly thereof, and means for raising and lowering said curtain, gun, and platform assembly.

6. In a blast-room, an enclosure, a part of the wall of said enclosure comprising a set of vertical guide-ways and a flexible curtain section movable in said guide-ways, a jet gun carried by said curtain section and discharging inwardly of said enclosure, an operator's platform carried by said curtain section exteriorly of said enclosure, means for raising and lowering said curtain-gun-platform assembly in said guide-ways, and means operable by an operator on said platform to control said raising and lowering means and the operation of said jet gun.

7. In a blast-room, an enclosure, a part of the wall of said enclosure comprising a set of vertical guide-ways and a flexible curtain section movable in said guide-ways, a jet gun carried by said curtain and discharging inwardly of said enclosure, an operator's platform carried by said curtain exteriorly of said enclosure, means for raising and lowering said curtain-gun-platform assembly in said guide-ways, means under control of an operator on said platform to control said raising and lowering means, limit means to prevent overtravel of said assembly in either direction, and means operable by an operator on said platform to control the operation of said jet gun.

8. A blast-room comprising a floor, said floor having a pit, a vestibule overlying a part of said pit, said vestibule comprising side walls and a top wall, a vertically movable wall closing the room side of said vestibule, an operator's platform carried by said movable wall within said vestibule, a blast-gun adjacent said platform and discharging into said blast-room, and means controllable by an operator on said platform for raising and lowering said platform, wall, and blast-gun and for controlling the discharge of said blast-gun.

9. A blast-room comprising a floor, said floor having a pit, a vestibule overlying a part of said pit, said vestibule comprising the pit bottom and side walls and a top wall, guide-rolls extending across said vestibule at the room side thereof adjacent the top wall and adjacent the pit bottom respectively, vertical guide-ways extending between said guide-rolls adjacent the room side of said vestibule, reel-rolls extending across said vestibule at the outer side thereof adjacent the top wall and adjacent the pit bottom and in substantially spaced relation to said guide-rolls, a flexible curtain extending through said guide-ways and trained over said guide-rolls, and having its ends reeled upon and secured to said reel-rolls, a least one of the portions of said curtain extending from said guide-rolls to said reel-rolls lying in close juxtaposition to the adjacent one of the top and bottom walls of the vestibule, an operator's platform within said vestibule and secured to said curtain to be raised and lowered as said curtain is reeled in one or the other direction, a blast gun movable with said platform and discharging into said blast-room, means for driving said reel-rolls and for maintaining said cur-

tain taut between them, and means carried by said curtain controllable by an operator on said platform for controlling the operation of said reel driving means and the operation of said blast-gun.

10. In a blasting room curtain assembly, a pair of reel rolls, a curtain reelable from one of said rolls to the other, a sprocket turning with each of said rolls, a chain connecting said sprockets to control the mutual operation of said rolls, said chain having a curtain tensioning leg pulling upon each sprocket in a direction to effect reeling of the curtain on its associated roll and a return-leg extending between the other sides of said sprockets, said chain having a tension spring in its curtain tensioning leg and having its return-leg relatively taut when in the position at which equal amounts of said curtain are reeled on each of said rolls.

11. In a blast-room, a vestibule comprising parallel, bracingly positioned, side walls presenting vertical guide-ways, a curtain wall slidable in said guide-ways, a universal nozzle mounting carried by said curtain, means for feeding water at high pressure through said mounting, a hydraulic sandblast gun mounted on said universal mounting and supplied with water therefrom, means for supplying abradant to said gun, the reaction of said high pressure blast being transferred through said universal mounting to said curtain, and transferred therefrom through said guide-ways to said parallel, bracingly positioned, side walls.

12. A blasting room comprising a vertically movable blast-gun inside the room and a vertically movable operator's platform outside the room, a window in the room wall separating said gun and platform positioned to enable an operator on said platform to observe the operation of said blast-gun, means for simultaneously raising and lowering said gun and platform, and means under control of the operator on said platform for controlling said last named means.

13. A blasting room according to claim 12, said room wall comprising a flexible reel-carried curtain in turn carrying said gun, platform, and window; and said gun, platform, and window being movable vertically by reeling of said curtain on its reels.

14. A blast-room vestibule and operator's station comprising guiding and reeling rolls adjacent the inner and outer top and bottom portions of the vestibule, a flexible curtain carried by said guiding and reeling rolls, and closing the blast-room face of said vestibule, an operator's platform connected to and vertically movable with said curtain, the guiding and reeling rolls at the top of said vestibule being spaced from one another by substantially the depth of said operator's platform whereby an operator on the platform is provided with head room within the vestibule, and inwardly of said upper reeling roll.

15. A blast-room vestibule and operator's station according to claim 14, in which the lower guiding and reeling rolls are located in a pit below the normal floor level, and in which said operator's platform is aligned with said normal floor level at one position in its traverse.

16. A blast-room vestibule and operator's station according to claim 14, further comprising means carried by said curtain adjacent said operator's platform and under control of an operator thereon for controlling operation of said reel-rolls to raise and lower said operator and platform, and limit means associated with said last-

named means to stop elevation of said platform at the point at which the operator's head is housed behind said upper reel-roll, but out of contact with the run of said curtain extending from said upper reel-roll to said upper guide-roll.

17. A blasting room comprising a vertically movable wall section, a bracket secured to the room-side of said wall section and vertically movable therewith, a blast-gun carried by said bracket and mounted for at least limited universal movement relative thereto, flexible conduits at the room side of said wall section and connected to said blast gun for conducting blasting particles and high pressure fluid thereto, said bracket transferring the reaction of the high pressure blast to said movable wall section, and means for controlling the discharge of said blast gun from outside said movable wall.

18. A blasting room comprising a vertically movable wall section, a gun mount projecting from the room side of said wall section, carried by said wall section, and vertically movable therewith, a blast gun carried by said mount on the room side of said wall section and having at least limited universal movement relative thereto, flexible conduit means at the room side of said wall section and connected to said blast gun for con-

ducting blasting particles and high pressure fluid thereto, said mount transferring the reaction of the high pressure blast to said movable wall section, and means for controlling the discharge of said gun from outside the movable wall.

19. A blasting room comprising a vertically movable wall section, a blast gun on the room side of said wall section and mounted thereon for at least limited universal movement relative thereto and vertical movement therewith, flexible conduit means at the room side of said wall section and connected to said blast gun for conducting blasting particles and high pressure fluid thereto, the mounting of the blast gun on said movable wall section transferring the reaction of the high pressure blast to said movable wall section, and means for controlling the discharge of said blast gun from outside said movable wall.
